UNITED STATES PATENT OFFICE

WALTER J. ARING, OF CLEVELAND HEIGHTS, AND WILLIAM E. ADAMS, OF AKRON, OHIO, ASSIGNEES, BY DIRECT AND MESNE ASSIGNMENTS, OF ONE-FOURTH TO WILLIAM E. ADAMS, OF AKRON, OHIO, ONE-FOURTH TO WARREN F. MOSMAN, OF EAST CLEVELAND, OHIO, AND ONE-HALF TO SAID ARING

BANK-VAULT STRUCTURE

Application filed March 31, 1926. Serial No. 98,825.

This invention relates to an improved bank vault structure and is particularly advantageous in branch or neighborhood banks which are increasing so rapidly in number in the out-lying districts of the larger cities.

Heretofore it has been the practice, in the construction of branch banks, to include the vault as a permanent part of the main building, the reinforced concrete outside walls of the bank building defining the dimensions of the vault area, and the metal lining of the vault being secured to the inner faces of the walls after the walls are up. It is understood, of course, that the vault area accommodates not only the safety deposit boxes but also affords storage space for trunks, etc. With the old style of building and method of constructing the same, as just referred to, it is of course a matter of conjecture as to the proper area to allow for the vault, taking into consideration the anticipated growth of the bank and the increased demand for vault space. Accordingly, it is necessary, at the time of construction to allow a substantial excess of vault area to take care of future demands; otherwise it will sooner or later be necessary to tear out the reinforced concrete wall of the bank building in order to enlarge the vault area. However, the provision and reservation of a substantial excess area for future expansion involves the carrying of such excess area, or a great part of it, for a considerable period of time, perhaps years, without any financial return. The result is that, according to actual experience, banking concerns generally classify their vaults as liabilities rather than assets.

It is therefore the object of this invention to provide a vault structure in which it is possible to extend the area of the same from time to time as may become necessary and without the very laborious and expensive task of tearing down and reconstructing a reinforced concrete wall of the bank building proper. In other words, the present invention is intended to change the bank vault from a liability to an asset by rendering the same readily expandable or contractible.

More specifically, it is our object in constructing a vault, to first connect together

the desired number of standardized steel plates, according to the vault capacity desired, and then to built a wall of tile blocks or the like entirely about the same, with the possible exception of the bottom wall. By 55 making the plates of predetermined shape and size, and by providing uniform means of detachable connection, it is a comparatively simple matter to vary the capacity of the vault by the subtraction or addition of such metal plates which, according to our invention, will be kept in stock.

It is also an object of this invention to provide a means for automatically extinguishing the flame of a torch in the process of attempting to burglarize the vault, this object being accomplished by means of shallow dead air spaces between the inner and outer plates. More specifically, such means comprises a plurality of integrally formed and suitably spaced pockets, the walls of which serve also as a reinforcing means in the main wall structure.

Fig. 1 is a perspective view, partly broken away; Fig. 2 is a transverse sectional view 75 taken on line 2—2 of Fig. 1; Fig. 3 is a detail partial view of an outer plate; and Fig. 4 is a perspective partial view of a modified form of our invention.

It is to be understood that our improved vault may be set up within the bank structure proper and wholly independent of the main walls of the bank building. Thus, our vault is a portable, sectional structure comprising detachably connected plates of standardized 85 form.

The four side walls as well as the top and bottom walls of our vault are of like construction. Each wall comprises a plurality of outer plates 1 of one and one-half inch 90 torch-resisting steel, and inner plates 2 of one-half inch open-hearth steel. In our first form of invention, the inner plates are all of the same dimensions, excepting the auxiliary plates 2^a at the corners, these 95 smaller plates being half-width. The outer plates are all of the same dimensions. The side wall plates extend over the edges of the top and bottom plates, and the end plates extend over the edges of the side wall plates. 100

The inner and outer plates, in each case, abut each other, the joints of the inner and outer sets being out of registry or in other words in staggered relation. The inner and outer plates are connected in such overlapping relation by means of removable screw bolts 3, the manner of drilling and tapping the bolt holes being described below. The plates are detachably connected at the corners by means of angle members 4 which are also bolted in position. The tiling 5 surrounds the four side walls and covers the top wall as well. Tiling may also be provided for the bottom wall of the vault, or the bottom of the vault 15 may rest directly upon the floor of the bank building.

In the modified form of invention shown in Fig. 4, the auxiliary plates 2^a are omitted and the angle members 4' are arranged on the inside in such a manner that the flanges 20 of the angle members abut the adjacent inner plates 2 so as to perform the function of the auxiliary plates as well. In other words, in this modified form of structure, the angle members perform two functions—namely, that of connecting the parts together at the corners and also the function of the auxiliary plates 2^a. Thus, in this particular form of structure, all of the plates, both inner and outer, are of the same width and are therefore of uniform dimensions throughout.

In both forms of our invention, the bolt holes are so spaced that they can be drilled and tapped with a pair of inner and outer plates lying in the same overlapping relation as in the assembled structure. This will be understood when, for instance, the first hole is spaced 3 inches from the edge of the plate and the succeeding holes are spaced 12 35 inches, 6 inches, 12 inches and 3 inches, respectively, across a 36 inch width plate. This arrangement of holes is illustrated in Fig. 2 of the drawing. With this relative arrangement of plates and bolt holes, the same set-up of template and jig can be used 40 throughout and the operations are thereby reduced to a minimum. And because of this standardization of plates and the relative arrangement of the connecting means 45 thereof, the cost of labor is kept down to a minimum.

In order to enlarge the vault, for instance in the first form of invention as here illustrated, the tile wall is first removed at the 50 one end and the end wall plates are removed together with the auxiliary plates 2^a. Then one or more full width inner plates can be added with the accompanying outer plates 1, according to the increased area desired, 55 and the end wall can then be restored with the auxiliary inner plates 2^a. Finally, the tile wall will be replaced. Or, in the case of the modified form of our invention, the tiling and plates at one end of the vault will be 60 removed, together with the corner angle 65

members, the desired number of side wall plates added, and the end wall then restored.

In extending either of the two forms of vault structure, as will be apparent, the same overlapping of the inner and outer plates will be preserved, the one half of the additional inner plate taking the place of the auxiliary plate in the one case; while in the other case, it replaces the corresponding flange of the angle member. Thus, the additional combination of an inner and outer plate arranged in overlapping relation, might be regarded as a wall unit; and it is to be understood that any number of such units may be added, according to the 70 enlargement of vault area desired. From the above description of the bolt holes, it will be seen that the attachment of one or more such wall units, with the holes already drilled and tapped, is a comparatively simple 75 matter.

With the overlapping arrangement of the inner and outer plates, as shown and described, these two sets of plates can be bolted together to form the several individual walls, 80 without requiring any further securing means, so far as the walls themselves are concerned. With this arrangement, it is also possible to have the plates of each set, (inner and outer), in abutting relation, with 85 the result that the plates lie flush with each other throughout the entire structure. Furthermore, in the modified form of our invention, as shown in Fig. 4, the flange of the corner angle members are also flush with 90 the inner plates.

The angle members may be made of either open-hearth steel or torch-resisting steel, and of the desired gauge, according to whether they are placed on the inside or outside of the vault structure. When placed on the outside, they will preferably be made of torch-resisting steel, and when on the inside, they will be of the same gauge of open-hearth steel as the plates 1, so as to lie flush 95 therewith. Other compositions of metal may 100 of course be used.

As a further means of securing the vault against unauthorized tampering, as for instance with the familiar oxy-acetylene torch, 105 we have so formed the inner faces of the outer plates 1 that when assembled with the inner plates 2, there will be formed the dead-air 110 spaces 6. The purpose of such shallow dead-air spaces or pockets is to extinguish the 115 flame of a torch as soon as it reaches this point. These pockets are so located that they will not extend across or communicate with the joints between the inner plates. It is to 120 be understood that the number of these pockets may be increased as may be desired. These 125 spaces or pockets do not communicate with each other or with the outside atmosphere and hence they have no fresh air supply or means of ventilation, and the hot products of com- 130

bustion normally created by the burning off the vault itself. The present improved vault, such a torch have no means of escape. In case a torch should be applied to the outside of a plate 1, in an endeavor to burglarize the vault, such an attempt will be delayed and hence discouraged by the automatic extinction of the torch flame upon reaching the shallow dead-air pocket. The hot products of combustion resulting from the burning torch will tend to smother the flame, since they have no means of escape from the dead-air pocket, and the shallowness of the pocket will have a snuffing effect upon the flame. Consequently, the flame is extinguished practically immediately upon reaching the shallow restricted pocket. Since these pockets do not communicate but are independent of each other, it will be seen that the blowing of a second hole through the plate at a point removed from the first, will merely lead to another dead-air pocket and will not open up a circulation of air through such dead-air space. By increasing the number of such pockets, the danger of there being created a circulation through the dead-air space may be reduced to an extreme minimum. The walls 6 between the dead-air pockets serve also as a means of reinforcing the wall itself. If so desired, the dead-air pockets may be so arranged that the bolt holes will extend through only the full portions 6^a, although they are here shown as extending through the dead-air pockets. The plates 6 are cast with the closed end portions 6^b.

This vault structure, as herein set forth, meets the requirements of the underwriters and, for the reasons above stated, it enables the bank to realize a profit on what has heretofore proved a financial loss.

Another advantage consists in the possibility of placing the vault in a position other than that at the extreme rear of the bank building, which is true of the form of structure now in use. This objectionable situation is due, as above explained, to the fact that the vault is constructed as an integral part of the bank building itself, and by allowing excess space for additional cages, etc., in the bank lobby, the vault is, according to the old practice, forced to occupy a position away from the front and hence out of full view. The present invention, which enables the vault to be located wherever desired, independently of the size of the bank building, means therefore an increased degree of safety due to the lessened danger of attempts at burglary.

Furthermore, whereas, with the style of structure now in use, it is impossible to continue the vault service uninterruptedly during an enlargement of the bank building, for reasons already explained, with the independent vault structure the tearing out and extending of the bank walls, as may be found necessary from time to time, will not interfere with

the vault itself. The present improved vault structure can be moved from one position to another on the bank floor, as maybe desired. Thus, with our improved vault structure, the capacity of the bank proper can be expanded from time to time without interrupting the vault service. In a word, our style of vault makes its possible to keep the capacities of the bank lobby and vault in proper step with each other during the growth of the bank, and without the excessive overhead carrying expense or interruption of service.

A further advantage of our invention resides in the fact that it is possible, in moving a vault, to remove the several walls as assembled units without the necessity of completely dismantling each wall into its component parts. This means a great saving in time and labor as well as material, as compared with the old practice which is made necessary by the style of vault structure now in use.

It is to be understood, of course, that the specific dimensions of parts might vary from the present showing, without departing from the essence of our invention, the exact embodiment, as herein set forth, being intended merely for purposes of illustration. It is to be understood also that our improved vault may be divided into the usual compartments, as may be desired, the illustration of partitions being omitted from the present drawing so as to avoid possible confusion.

What we claim is:

1. A bank vault structure comprising detachably connected multiple units, said units being standardized in size and uniform in shape throughout the entire structure and being provided with uniform securing means, whereby the capacity of the vault may be readily contracted or expanded at will by the subtraction or addition of standardized units. 100
2. In a bank vault structure, sets of inner and outer wall plates, the plates of each set being of standardized size and shape throughout, uniform means for detachably connecting the inner and outer plates of each wall in staggered butt-joint arrangement with each other, and uniform means for detachably connecting the several walls, whereby the capacity of the vault may be readily contracted or expanded at will by the subtraction or addition of standardized wall units. 110
3. A bank vault structure comprising a plurality of walls, each wall having detachably connected multiple units, said units being standardized throughout the entire structure and being provided with uniformly arranged securing means, said plates and securing means being so constructed and arranged with respect to each other that the area of the vault can be varied by the addition or subtraction of one or more prede- 125

termined units without disturbing the uniformity of said units.

4. In a bank vault structure, sets of inner and outer main wall plates of uniform size and shape, said inner and outer plates being arranged so as to overlap each other partially, auxiliary plates of a width corresponding to the extent of overlap between said inner and outer plates, and uniform means for securing said plates together, whereby the area of the vault can be varied by the ready addition or subtraction of one or more combinations of inner and outer main wall plates.

15 5. In a bank vault structure, sets of inner and outer wall plates, the plates of each set being of standardized size and shape throughout, uniform means for detachably connecting the inner and outer plates in staggered butt-joint arrangement with each other and for detachably connecting the several walls together, whereby the capacity of the vault may be readily contracted or expanded at will by the subtraction or addition of standardized wall units.

30 6. In a bank vault structure, sets of inner and outer wall plates, the plates of each set being of standardized size and shape throughout, uniform means for detachably connecting the inner and outer plates of each wall in staggered butt-joint arrangement with each other, the plates of one set extending beyond those of the other set at the corners, and detachable angle members arranged flush with the plates for connecting the several walls at the corners, whereby the capacity of the vault may be readily contracted or expanded at will by the subtraction or addition of standardized wall units.

40 7. In a bank vault structure, sets of inner and outer wall plates, the plates of each set being arranged in abutting relation, and the joints of the sets being out of registry with each other, adjacent plates being provided with dead-air pockets therebetween, said pockets being arranged between and out of communication with said joints.

50 8. In a bank vault structure, a self-contained and self-supporting lining composed of a plurality of walls, each wall comprising a plurality of detachably connected multiple units, said units being standardized throughout the entire structure and being provided with uniform securing means, said parts being so constructed and arranged that the completely assembled lining structure is readily and bodily movable as a unit and is readily expandible or contractible by the addition or subtraction of standardized wall units.

60 9. A bank vault structure consisting of a self-contained and self-supporting lining, said lining being composed of a plurality of walls, each wall comprising a plurality of detachably connected multiple units, said units

being standardized throughout the entire structure and being provided with uniform securing means, said parts being so constructed and arranged that the completely assembled lining structure is readily and bodily movable as a unit and is readily expandible or contractible by the addition or subtraction of standardized wall units, and a surrounding wall structure of tiling or the like enclosing said lining.

70 10. A bank vault structure comprising a plurality of walls, each wall having detachably connected inner and outer plates, said plates being standardized in size and shape and being provided with uniformly arranged bolt holes throughout the entire structure, whereby the wall plates may be readily added or subtracted.

80 11. In a bank vault structure, sets of inner and outer wall plates, the plates of each set being of standardized size and shape throughout, all of said plates being provided with uniformly arranged bolt holes for detachably connecting the inner and outer plates of each wall in staggered butt-joint arrangement with each other, and means for detachably connecting the several walls, whereby the capacity of the vault may be readily contracted or expanded by the subtraction or addition of wall plates.

90 In testimony whereof we affix our signatures.
